HARNESS FOR LOOMS OR THE LIKE.

1,399,298.

Specification of Letters Patent.

Patented Dec. 6, 1921.

Application filed November 4, 1915. Serial No. 59,562.

To all whom it may concern:

Be it known that I, EDGAR F. HATHAWAY, citizen of the United States, and resident of Boston, Massachusetts, have invented certain new and useful Improvements in Harness for Looms or the like, of which the following is a specification.

This invention relates to loom harness and is intended to provide simple, durable, and efficient means of preventing the separation of the two legs or branches of the looped cord by which the heddle eyes are suspended and to avoid the consequent shifting or displacement of the heddle eye or thread eye from its proper position in the harness.

In commercial practice the suspension cords of the heddles are passed over the top of a suspension bar and looped through a small hole in the eye or warp-retaining member of the heddle, two branches of said cord being secured together by shellac or other adhesive just above the thread eye. This method of connecting or securing together the two branches of the cord is open to the objection that it is not absolutely reliable since the adhesive material may become softened by atmospheric changes or may crack, thus permitting the two strands or branches of the suspension loop to pull apart. Such pulling apart not only acts to interfere with the proper positioning of the heddle eye, but allows it to shift on the cord so that the tension on the two branches of the cord is unequal, thereby often producing breakage.

The tying together of the two members or branches of the suspension cord is not satisfactory because the presence of any knot or projection seriously interferes with the proper action of the loom harness, since such shoulder or projection tends to catch against adjacent warp threads carried by another set of heddles, besides tending to produce chafing of the warp threads of the heddles due to the relative reciprocation of the different sets of heddles. The present invention is intended to obviate all difficulties by so fastening or securing the branches of the respective heddle members together that no obstruction or projection is formed, while at the same time the branches of the suspension cords are positively and reliably held together.

In the accompanying drawings I have illustrated the preferred embodiment of the

present invention as applied to a loom harness, in which—

Figure 1 is a front elevation showing a series of heddles fastened in accordance with this invention.

Fig. 2 is a side elevation showing two adjacent heddles slightly spread apart.

Fig. 3 is an enlarged detail view showing the lower end of the looped cord passed through the heddle eye with a fastening member applied.

Figs. 4 and 5 are detail views of the fastening member or clip employed for this purpose.

Fig. 6 is a horizontal section through a heddle cord just above the encircling fastening clip.

In the drawings the upper and lower heddle supporting bars *a* are of the usual construction to receive the upper suspension cord *c* and the lower cords *e* which are passed around the respective bars after the usual practice and which are held in place by the anchoring cords *a'*.

The heddle eyes *b* are provided with the elongated central opening *b'* through which the warp threads are passed and are also formed with small perforations *b''* at their opposite ends through which the heddle cords *c*, *e*, respectively, are passed in order to suitably suspend the eyes in operative position. In Fig. 2, two adjacent heddles are shown somewhat separated from their position of alignment in order that the looping of the suspension cords may be clearly understood.

The suspension cords *c* are passed over the upper bar and through the small suspension perforations *b''* of the thread eye. Instead of being glued together, however, I employ a small clip *d* made of any suitable material such as thin sheet metal, which is passed around the two adjacent branches of a suspension cord just above the thread eye which it supports and which is clenched or clamped tightly around said branches of the cord, as best shown in Fig. 3.

As it is important that any projection, shoulder, or ridge of any kind, against which any warp threads could catch, should be avoided, I prefer to use a form of fastening clip similar to that shown in Figs. 4 and 5, which is made U shaped with a single prong *d'* on one side opposite to a cor-

responding notch or recess formed in the other side, which leaves on the other side two offset prongs d^2 so that when the clip is tightly set or clenched upon the cord the tongue or prong d' will lie inside the recess formed between the pair of prongs d^2 so that the strands of the cord may be encircled without producing any over-lapping of one branch of the clip above the other. By 10 means of suitable pliers or other setting device the clips may be clenched so tightly into the fiber of the cord that it lies slightly below the normal outside line of the two cords adjacent to the fastening, as clearly shown 15 in Fig. 3.

It will, therefore, be seen that there is not the slightest obstruction or shoulder which can catch against the adjacent warp threads, while at the same time the lower looped end 20 of the cord has its two branches fastened together in a positive manner which precludes the possibility of any slipping with relation to each other and makes it impossible for the heddle eye to change its position along 25 its suspension cord.

I have shown the fastening clips wrapped around and clenched upon the upper or suspension cords of the harness eyes since or-

dinarily the use of the clips on the upper cords is sufficient for practical purposes but 30 it will be understood that I do not limit myself to that particular location of the clips.

What I claim is:

A heddle cord for holding the heddle eye 35 of a loom harness embracing in its construction a cord looped through said eye and doubled back upon itself to form a closely assembled double strand, a fastening clip comprising a single piece of flexible sheet 40 material wrapped completely around said double strand under sufficient pressure to embed the whole clip in the encircled portion of the double strand so as to afford no projection beyond the outer surface of the 45 adjacent portions of the double strand, the free ends of said clip being laterally offset when so embedded to pass beyond each other circumferentially of the double strand thereby avoiding the overlapping of one end 50 of the clip above the other, substantially as described.

In witness whereof, I have subscribed the above specification.

EDGAR F. HATHAWAY.
